UNITED STATES PATENT OFFICE.

JULES DEHON, OF PHILADELPHIA, PENNSYLVANIA.

CARPET-CLEANING MACHINE.

1,287,651.

Specification of Letters Patent. Patented Dec. 17, 1918.

Application filed January 5, 1918. Serial No. 210,584.

To all whom it may concern:

Be it known that I, JULES DEHON, a citizen of the United States, residing in the city and county of Philadelphia, State of Pennsylvania, have invented a new and useful Carpet-Cleaning Machine, of which the following is a specification.

This invention relates to the art of cleaning carpets, rugs and other fabrics or textiles, by operations of beating and scrubbing which involve the use of brushes, beaters, air-ejectors, dust-sucking, and other devices for effecting a cleaning operation without injury to the article to be cleaned.

Specifically considered, my present invention is an improvement upon an invention made by me which forms the subject-matter of United States Letters Patent No. 1,196,527, dated August 29th, 1916, to which reference is to be made,—and it comprehends particularly special devices by means of which the carpet is connected with the carrying apron by which it is conveyed and caused to be presented to the devices which effect its cleaning,—and also comprehends other devices by means of which the carpet is held against the apron during its travel, and still other devices by means of which the cleaning brushes are maintained in operative contact with the apron.

The general elements which constitute the machine of my patent referred to and which are embodied in my present machine, are referred to in my patent and as general elements *per se* are not herein claimed by me.

For the purpose of illustrating my invention, I have shown in the accompanying drawings a certain type and embodiment of it which is at present preferred by me because in practice it has given satisfactory and reliable results. It is to be understood, however, that the various components in which my present invention is shown as embodied can be variously arranged and that my invention is not, therefore, limited to the precise arrangement which is typified in the construction shown in the accompanying drawings and hereinafter described.

Obviously, modifications of the specific devices represented, described and claimed, may be easily effected.

In the drawings, Figure 1 represents a view in perspective of a carpet cleaning machine embodying my invention;

Fig. 2 represents a vertical, side, sectional elevation of the machine represented in Fig.

1, assumed to be taken in an approximately central, vertical plane, and illustrating in connection with the machine of Fig. 1, the beating and dust-sucking devices of which I make use;

Fig. 3 represents a fragmentary, end elevational, face view of the fastening mechanism to which I resort to connect the carpet or article to be cleaned with the traveling apron;

Fig. 4 represents a transverse, sectional detail of the fastening mechanism of Fig. 3, the section being taken upon the dotted line 4—4 of said Fig. 3;

Fig. 5 represents a side, elevational detail of means for maintaining a cleaning brush against the fabric upon the apron;

Fig. 6 represents a fragmentary, side, sectional elevation of a portion of the apron and my improved squeezing device for maintaining the carpet in close contact with the traveling apron while expressing the excess of liquid used;

Fig. 7 represents a detail in side elevation, of means for maintaining a pressure roll in contact with the carpet to press the latter upon the apron;

Fig. 8 represents a side elevational detail of one of the cleaning brushes removed from the machine; and

Fig. 9 represents in fragmentary perspective the squeezing device of Fig. 6.

Similar numerals of reference indicate corresponding parts in the several figures.

Referring to the drawings:

The base frame of the machine is of any desired construction but preferably of structural iron members to which the numeral 1 is applied, and which are conveniently connected with a bed plate 2, so as with it to form a drip tank to receive the drippage of the cleaning fluids.

3 are pillars or standards rising from the base frame and serving to support both transverse beams 4 and longitudinal beams 5, which are so connected as with the pillars to form a framework relatively to which the apron as an entirety and the brush and cleaning devices are mounted.

The endless apron or carpet carrier 6 is of any preferred construction but conveniently composed of slats, is transverse of the framework, and is mounted upon endless carrying sprocket chains 7, two or more of which in parallel relationship serve as the medium of its support and travel.

In the apron organization represented, five carrying sprocket wheels 8, 9, 10, 11 and 12 are shown as being mounted upon rotary shafts 8^x, 9^x, 10^x, 11^x and 12^x which are housed in bearings of any preferred type, for instance such as 13, Fig. 1.

The driving of the apron in the direction of the arrows upon the drawings, is conveniently effected by sprocket wheels on said rotary shafts, of any preferred type, driven primarily by the power wheel 14.

15, 16 and 17 designate cylindric cleaning brushes,—18, 19 and 20, cleaning fluid ejectors by which I apply cleansing and cleansing fluid to the surface of the carpet to be cleaned, and 15^x, 16^x and 17^x designate electric motors for the brushes 15, 16 and 17. Excepting said motors, the devices hereinbefore described are in general respects similar to those shown in said patent.

In order to maintain the brushes in the desired adjustable contact with the carpet, I resort to the devices which are represented in Figs. 5 and 8,—in which 21 designates a brush shaft of, for instance, the brush 16, which shaft is mounted in a bearing 22 formed upon the end of a radial lever 23 fulcrumed on a rotary shaft 24 housed in the bearing bracket 25 and conveniently supported from a pillar 3,—which shaft, being of course driven by one of the motors, as 16^x, carries the driving pinion 26 which meshes with the driven pinion 27 on the brush shaft 21.

35 From the free end of the brush lever 23 depends a counterweight 28 which tends to maintain the brush 16 in such contact with the carpet controlled by the adjusting screw 29 which is mounted on the frame of the machine, as shown in Fig. 5, and bears upon the inner end of said brush lever 23.

30 designates a rotary beater of the character of that used in the machine of my patent referred to, the arms of which beat 45 upon the carpet 31 or other fabric to be cleaned, and, loosening the dust from the meshes or interstices of its web, beat it through the sieve 32 which incloses the upper opening of the suction-trough 33 50 equipped with a suction fan or blower 34, the outlet of which is 35 as typically illustrated in Fig. 2.

The fastening mechanism which I employ for fastening or securing the free end of 55 the carpet or fabric to be cleaned to the apron, is illustrated in Figs. 2, 3 and 4 and is of the following construction.

36 is a bar of channel iron of a typical concave or hollow form, preferably such, 60 for instance, as is clearly illustrated in Fig. 4, which is of the length of one of the slats of the carrying apron, and in its application to said apron takes the place of, that is to say is substituted for, one of the slats,—being conveniently connected with the carry-

ing chains of the apron in the same manner as are the slats themselves.

In its application to the apron the channel iron faces outward as shown in Fig. 2, that is to say, its open face is exterior of the 70 apron as an entirety, and its flat back faces inwardly. It constitutes a combined slat and receptacle, so to speak, which is adapted to contain a carpet fastening means of special construction, namely a bar of angle iron 75 37 which is secured to it by bolts 38, and which faces outwardly so as to be adapted to receive beneath its lower member the lower limb of an angle iron which I term the carrying iron or bar 39.

Both the angle iron 37 and the carrying iron 39 are preferably of the length of the channel iron 36 so that in their applied relationship to said channel iron they fit within, and extend longitudinally throughout, it.

Supported on the lower member of the channel iron 36 and extending right angularly preferably up to the rear face of said channel iron, are a plurality of lugs 40, 90 disposed preferably in groups at different distances along the interior of the channel iron, which receive and support the lower member of the carrying iron 39 when the latter is introduced within the channel iron 95 and between the lower member of the carrying iron 39 and the lugs aforesaid, as will be best understood from Fig. 4.

To the front face member of the carrying iron 39 is attached by a rivet 41, or equivalent fastening, a flexible connecting web 42 which is of equal length with the length of the channel iron, that is to say, of a length about equal to the breadth of the apron, and to this connecting web which may be of canvas or kindred flexible material, I connect the carpet 31 to be cleaned, by attaching eyes 43, Figs. 2 and 3, which are simply attaching devices of any preferred character by means of which the free end of the carpet 110 can at will be connected with or detached from the connecting web 42.

Longitudinally extending within the channel iron 36 is an operating rod 44, housed for end-for-end movement in slide 115 bearings 45 within the channel iron, and adapted to be thrown to the right or the left as shown in Fig. 3 by an operating handle 46 extending through an elongated aperture 47 through the rear wall of the 120 channel iron, which handle is adapted to be manipulated by the operator by simply taking hold of it and moving it transversely in or out from the side of the apron.

48 is an elbow lever fulcrumed at 49 on 125 the rear face of the angle iron 37, and as to its vertical member extended between two bosses 50 and 51 fixed on the operating rod 44, and, therefore, adapted to be encountered by either one of them and according 130

to the direction of movement of the operating rod 44 to occasion the elevation or depression of its own horizontal arm which I have designated 48^x.

5 To the outer end of the arm 48^x is suspended a locking latch 52 connected with said arm by a pivot 53, which bolt passes through a slot 54 in the base of the carrying iron 39 and also, through the slot 55 in the 10 channel iron 30.

56 designates a plate-spring fastened at one end by bolts 57 to the lower member of the angle iron 37, and at its other or free end slotted to permit the shank of the locking latch 52 to pass through it, as best shown 15 in Figs. 3 and 4.

In practice, I employ two or more of these locking latches 52 and bell crank levers 48, connected with and operated by the afore- 20 said rod 44, and in the attachment of the carrying iron 39 and its connecting web 42, the bolts and bell-crank levers are in the position represented in dotted lines in Fig. 3, and when the attachment has been com- 25 pleted are in the position represented in full lines in said Fig. 3.

When the rod 44 is moved in one direction by the handle 46, the latches 52 are raised through the slots 54 and the carrying iron 39 is released of the holding action of said latches, and said angle iron may be drawn 30 out of the channel iron or bar 36, and with it the web 42. Then the carpet can be disconnected from said web after which a fresh 35 piece of carpet may be connected with said web, when the angle iron 39 is again introduced into the channel bar 36, and the rod 44 operated whereby the lever 45 lowers the latches 52 and locks said iron 39 with the 40 iron 37. The piece of carpet may be subjected to the action of the beaters 30 over the trough 33 and then carried down around the machine by the endless apron during 45 which time it will be subjected to brushing, the fluid-cleaning material, squeezing and other manipulation as before.

This specific device as an entirety is one of simplicity and reliable operativeness, and serves as a means for quickly and conveniently attaching and detaching the carpet to and from the endless apron.

In Figs. 2, 6, and 9 I have represented a squeezing device which is the last of the active elements to operate upon the carpet 55 after the beating devices, the brushing mechanism and the washing or cleansing fluid mechanisms have operated upon it.

In this device 58 represents a squeezing web or strip of flexible material such, for 60 instance, as rubber cloth, which is held within a collar-like head 59, preferably cylindri- 65 form and formed with radially and outwardly extending parallel flanges 60, be- 65 introduced and retained by bolts.

The web extends transversely of the machine to a length preferably equal to the breadth of the traveling apron. The head 59 is of equal, or preferably slightly greater length than the web and at its ends is fixedly 70 secured to balance levers 61, fulcrumed at 62 to the framework, and having their free ends which extend beyond the fulcra provided with weights 63.

Obviously, the construction and mounting 75 of this squeezing device is such as to insure a constant pressure of the web against the carpet in its travel on and with the apron and a constant resultant expression of all 80 excess cleansing fluid or water from the carpet.

In Fig. 7, I have represented a pressure roll 64, which is adjustable to hold the carpet against the endless apron to prevent sagging of the former in the travel of the latter 85 upon and with the apron. This roll is as long or a little longer than the breadth of the apron, and its trunnions 65 have at each end bearings in suspended links 66 which are pivoted to adjusting bolts 67 connected 90 with the frame-work and adapted to be set in adjusted vertical position by lock nuts 68. The direct connection and support of this pressure roll relatively to the frame-work is through carrying arms 69, as clearly 95 shown in Fig. 7.

The brushes 15, 16 and 17 have each their own individual motors so as to enable them to be run at the same or different degrees of speed for purposes requiring the same. 100 there being occasions when a brush should be rendered inoperative when it can be thrown out of service without effecting the operations of the other brushes, and then each brush has its own adjustment so that 105 it can be set to cause the proper action on the carpet at its distinctive place of contact without regard to the other brushes.

Having thus described my invention, what I claim as new and desire to secure 110 by Letters Patent, is:—

1. In a carpet cleaning machine the following elements in combination:—a supporting frame-work,—an endless apron comprising a series of connected slats and a 115 channel iron interposed between two adjacent slats, said channel iron having a manually-operated locking mechanism for detachably connecting to it a flexible web to which the free end of the article to be cleaned is 120 adapted to be connected,—a flexible web the outer end of which is adapted to be removably connected with the channel iron of the apron and the inner end with the carpet,—means for supporting and occasioning the travel of the apron,—and cleaning devices co-operating with said apron to clean 125 the carpet.

2. In a carpet cleaning machine in which are combined an endless apron, means for 130

- beating, means for brushing, and means for washing a carpet,—a mechanism for connecting the end of the carpet to be cleaned with the apron, which consists of a channel iron, an angle iron within said channel iron, a spring-controlled manually-shiftable locking mechanism, also a carrying iron slotted to engage with the locking mechanism when introduced within the channel iron, and 10 also a flexible web connected with the carrying iron and adapted to be removably connected with the carpet.
3. In a machine of the class recited,—an apron comprising a series of connected slats 15 and a channel iron interposed between two adjacent slats, said channel iron having a manually operated locking mechanism,—in combination with a connecting web adapted to be manually connected or disconnected 20 with said locking mechanism and to be also connected or disconnected with the carpet to be cleaned.
4. In a carpet cleaning machine, a traveling support on the frame of the machine 25 for the carpet, means for operating said traveling support, a pressure roller for the carpet, a weighted lever on which said roller is mounted, said lever being movably mounted on said frame, and an adjustable 30 member fitted to said frame and connected with the lever to adjust the pressure of said roller on the carpet.
5. In a carpet cleaning machine, a traveling support on the frame of the machine 35 for the carpet, means for operating said traveling support, a rotary brush for the carpet, a weighted lever on which said brush is mounted, said lever being movably mounted on said frame, gearing on the shaft 40 of said brush and said lever for rotating said brush, and an adjustable member fitted to said frame and adapted to engage said lever to adjust the pressure of said brush on the carpet.
- 45 6. In a carpet cleansing machine, a traveling support on the frame of the machine for the carpet, means for operating said traveling support, a squeezing member, and a weighted lever movably mounted on the frame of the machine, the same having said squeezing member mounted thereon.
7. In a carpet cleaning machine, a traveling support on the frame of the machine 55 for the carpet, means for operating said traveling support, and means for connecting the carpet with said traveling support and releasing it therefrom consisting of a web-like member adapted to have the carpet attached thereto, a movable bar with which 60 said web is connected, a support for said movable bar, a channel member adapted to carry said support, said channel iron being connected with said traveling support, a movable latch adapted to engage said movable bar, and means on said channeled member adapted to operate said latch in opposite directions.
8. In a carpet cleaning machine, a traveling support on the frame of the machine 65 for the carpet, a movable bar with which the carpet is adapted to be connected, a movable latch adapted to engage said bar, a channeled member adapted to carry said bar, the same being connected with said traveling support, an elbow lever having one limb 70 mounted on a relatively fixed support, and the other limb pivotally connected with said latch, and a slideable rod on the frame of the machine having therein bosses on the opposite sides of the first named limb of 75 said elbow lever, whereby the latter may be thrown in opposite directions to raise or lower said latch.
9. In a carpet cleaning machine, a traveling support on the frame of the machine 80 for the carpet, a movable bar with which the carpet is adapted to be connected, a movable latch adapted to engage said bar, a channeled member adapted to carry said bar, the same being connected with said 85 traveling support, an elbow lever having one limb mounted on a relatively fixed support, and the other limb pivotally connected with said latch, a slideable rod on the frame of the machine having therein bosses on the 90 opposite sides of the first named limb of said elbow lever whereby the latter may be thrown in opposite directions to raise or lower said latch, and a resilient device on said piece adapted to bear against said elbow 95 lever and consequently said latch to hold the latter in locking position preventing disconnection of the piece of carpet from the piece on said traveling support.
10. In an organized carpet cleaning machine substantially of the character stated, 100 a plurality of rotatable brushes adapted to contact with the carpet in the movement of the latter through the machine, bearing members for the shafts of said brushes 105 mounted on the frame of the machine, said members having means for their adjustment independently of each other, and a motor member for driving each of said shafts, the motors being operative independent of each other.
